FLUE CONNECTION FOR GAS HEATERS

Filed Oct. 13, 1930

UNITED STATES PATENT OFFICE

1,932,711

FLUE CONNECTION FOR GAS HEATERS

Max Schwartz and William W. Norton,
San Francisco, Calif.

Application October 13, 1930. Serial No. 488,510

7 Claims. (Cl. 126—116)

Our invention relates to improvements in flue connections for gas heaters, and it consists in the combinations, constructions and arrangements hereinafter described and claimed.

- 5 An object of our invention is to provide a flue connection for gas heaters which has novel means for draining any condensation away from the heater and out of the flue so that this water will not rust away the flue or heater casing.
- 10 A further object of our invention is to provide a device of the type described in which the flue or vent pipe is secured to a connection that extends from the outer box of the heater on to the heater itself, this connection being so designed 15 as to prevent any fumes from passing into the heater box and to cause condensation from the vent pipe to drop clear of the furnace and the pipe.

Other objects and advantages will appear as the 20 specification proceeds, and the novel features of the device will be particularly pointed out in the claims hereto annexed.

Our invention is illustrated in the accompanying drawing, in which:

- 25 Figure 1 is a vertical section through a gas heater, portions being shown in elevation.
- Figure 2 is an enlarged plan view of the flue connection.

- Figure 3 is a section along the line 3—3 of 30 Figure 2,
- Figure 4 is an end view of the connection, and

Figures 5 and 6 are sectional views of modified forms of the invention.

In carrying out our invention we make use of a 35 gas heater of the type shown in patents numbered 1,666,367, issued April 17, 1928, and 1,700,559, issued January 29, 1929. Briefly this heater comprises a casting 1 having radiating fins 2, a lower housing 3 for carrying the burner (not shown), 40 and a jacket 4 that encloses the housing 3 and has an open end 5. An air-diverting jacket 6 encloses the casting 1 and has openings 7 with inclined projections 8 placing the space 9 within the jacket in communication with the space 10 defined by the walls 11 of an outer box. The 45 entire device is supported by a floor 12 and a perforated plate 13 has air inlet openings 14 for permitting cold air to pass downwardly into the space 10 and air outlet openings 15 for permitting hot air to pass upwardly from the space 9. A 50 gas valve 16 is controlled by a rod 17 in the manner set forth in the patented devices.

The parts described thus far form no part of 55 our invention except insofar as they cooperate with the parts now to be described. The gas

fumes find their way into the jacket 4 and from there are directed into a vent pipe or flue 18. Figure 3 shows the pipe 18 as being secured to a connection indicated generally at 19, and it is the construction of this connection which is the 60 novel point in the present invention. The connection has an inner cylindrical portion 20 with a tapered outer surface 21 for receiving the pipe 18. An apron 22 encircles the rear portion of the cylinder 20, and this apron terminates just 65 beyond an opening 23 in the outer box 11. Any water condensing in the pipe 18 will pass between the portion 20 and the pipe into a space 24 formed by the portion 20 and the apron 22. The inner surface 25 of the apron 22 is inclined so 70 as to direct the water toward the open end 26 of the apron. As already stated, this end projects beyond the opening 23, and therefore water dripping from the opening 26 will fall clear of the outer surface of the box 11. This water will 75 therefore have no effect in rusting the box 11.

The apron 22 has a flange 27 which is bolted at 28 to the box 11. A flange 29 is carried by the cylindrical portion 20 and is secured to the jacket 4 by bolts or other suitable fastening means 30 80 (see Figure 1). In this way the connection is securely clamped to the jacket and to the housing and prevents any gas fumes from entering the box 11.

It will also be noted that the inner open end 31 85 of the connection 19 is provided with a lip 32 and that water dripping from this lip due to condensation will drop clear of the inner surface of the jacket 4. The bottom of the jacket is open as at 5, and it will therefore be seen that the jacket 90 wall cannot be rusted away by the water. The bottom 33 of the box 11 is disposed beneath the connection 19 as shown in Figure 1.

In the usual heater the condensation forms in 95 the pipe 18 and drops upon the bottom 33 of the box 11 because the apron 22 is not provided. This causes the bottom of the box to soon rust away. Furthermore, it is customary to leave an open space in the box 11 for receiving the pipe 18, and should the pipe drop away from any cause, the 100 fumes would pass from the connection into the box 11 because of the non-provision of the apron 22. A space would be left between the outer end of the cylindrical portion 20 and the wall of the box 11.

The provision of the apron 22 performs a double function of conveying condensation away from the bottom 33 and of preventing the gas fumes from passing into the box 11 should the pipe 18 be accidentally removed. The placing of 105

110

the bottom 33 below the connection 19 and the elimination of condensation dropping upon this bottom does away with holes being rusted into the bottom and prevents a cold draft from the basement passing through these holes and into the room. The opening of the bottom of the jacket 4 with the provision of the lip 32 prevents condensation from rusting away any part of the jacket.

10 In Figure 5 we show a slightly modified form of the invention. The part of the cylindrical member 20 projecting beyond the flange 29 is threaded at 50 for receiving a lock nut 51. The nut 51 clamps the jacket 4 to the flange 29. A lip 52 integral with the cylinder 20 keeps any condensation dripping from the cylinder from contacting with the wall of the jacket. In all other respects this form of the device is identical to that already described, and like reference numerals will therefore be applied.

20 In Figure 6 we show another modified form of the invention in which the sleeve 20 and the apron 22 are made in two parts and are given the reference numerals 75 and 76. The part 76 has an annular flange 77 threaded at 78 for receiving a threaded portion 79 of the sleeve 75. A flange 80 corresponding to the flange 29 bears against the outer surface of the jacket 4, and a flange 81 similar to the flange 27 bears against the wall 11. The sleeve 75 extends beyond the inner end of the part 76 and through an opening in the jacket 4. A lip 82 prevents condensation from dropping on the jacket 4. The other parts of the device are identical to that shown in Figure 3, and therefore like reference numerals will be applied.

Although we have shown and described several embodiments of our invention, it is to be understood that the same is susceptible of various changes, and we reserve the right to employ such changes as may come within the scope of the claims hereto annexed.

We claim:

45 1. A vent pipe connection comprising a cylindrical member having an outwardly extending flange spaced a slight distance from one end, an apron covering the other end and extending therebeyond, said apron being spaced from said

50

cylindrical member except at its place of attachment.

2. A vent pipe connection comprising a cylindrical member having an outwardly extending flange spaced a slight distance from one end, an apron covering the other end and extending therebeyond, said apron being spaced from said cylindrical member except at its place of attachment and an outwardly extending flange disposed a slight distance from the free end of the apron. 80

3. A vent pipe connection comprising a cylindrical member having an outwardly extending flange spaced a slight distance from one end, an apron covering the other end and extending therebeyond, said apron being spaced from said cylindrical member except at its place of attachment, the flanged end of the cylindrical member having an extending lip portion at its bottom. 90

4. In combination, a heater casing, a heater box surrounding the same and a vent pipe connection supported between the casing and the box and comprising a tube adapted to telescopingly receive the vent pipe and an apron encircling the vent pipe and adapted to guide condensation products to the outside of the heater box. 95

5. A vent pipe connection comprising a tube adapted to have a vent pipe telescoped thereon and an apron on the tube and encircling the end of the vent pipe, the apron being secured to an intermediate portion of the tube so as to leave a short length of tube projecting clear of the apron. 100

6. In combination, a heater casing, a heater box surrounding the same and a vent pipe connection supported between the casing and the box and comprising a tube adapted to telescopingly receive the vent pipe and a member encircling the vent pipe and adapted to guide condensation products outside the space between the casing and the box. 110

7. In combination, a heater casing, a heater box surrounding the same and a vent pipe connection supported between the casing and the box and comprising a tube adapted to telescopingly receive the vent pipe, and an apron secured between the casing and the box and arranged to guide condensation products outside the space between the casing and the box. 115
